DESIGN FOR A TOY AUTOMOBILE OR THE LIKE

James L. Stack, Jr., Crystal Bay, Nev.

Application March 19, 1945, Serial No. 118,565

Term of patent 3½ years

(Cl. D34—15)

To all whom it may concern:

Be it known that I, James L. Stack, Jr., a citizen of the United States, residing in the city of Crystal Bay, county of Washoe, State of Nevada, have invented a new, original, and ornamental Design for a Toy Automobile or the Like, of which the following is a specification, reference being had to the accompanying drawing, forming a part thereof.

Fig. 1 is a side elevation of the toy automobile,

or the like, showing my new design; Fig. 2 is a plan view of the toy automobile; Fig. 3 is a rear end view of the toy automobile, and Figs. 4, 5 and 6 are cross-sections taken through lines 4—4, 5—5 and 6—6 of Fig. 1, respectively.

I claim:

The ornamental design for a toy automobile or the like, as shown.

JAMES L. STACK, JR.
